DECANTER

Ernest L. Du Pree, Weston, Conn., assignor to Schenley Industries, Inc., New York, N. Y., a corporation of Delaware

Application February 19, 1957, Serial No. 44,907

Term of patent 14 years

(Cl. D58—6)

Figure 1 is a side elevational view of a decanter, showing my new design;

Figure 2 is a cross-sectional view thereof, taken on the line 2—2 of Figure 1;

Figure 3 is a top plan view thereof;

Figure 4 is a cross-sectional view thereof, taken on the line 4—4 of Figure 1 on an enlarged scale; and

Figure 5 is a cross-sectional view thereof, taken on line 5—5 of Figure 3, on an enlarged scale.

The side of the decanter opposite that shown is the same as that illustrated herein.

I claim:

The ornamental design for a decanter, as shown and described.
